UNITED STATES PATENT OFFICE.

LYMAN R. SWETT, OF BOSTON, MASSACHUSETTS.

ENVELOP.

942,420.

Specification of Letters Patent.

Patented Dec. 7, 1909.

Application filed August 23, 1909. Serial No. 514,124.

To all whom it may concern:

Be it known that I, LYMAN R. SWETT, a citizen of the United States, residing at Boston, in the county of Suffolk and State of Massachusetts, have invented certain new and useful Improvements in Envelops, of which the following is a specification.

My invention is designed for receiving and holding contributions for different objects, as in church and Sabbath school collections, and includes several novel features now to be described.

The accompanying drawing illustrates the invention, in which—

15 Figure 1 is a plan of the blank from which the envelop is formed and having its gummed surfaces shown in shaded lines. Fig. 2 shows the blank with its body portion folded and sealed and with a modification of the sealing flaps. Fig. 3 is a plan view of a completed envelop, and Fig. 4 is an enlarged edge view of an envelop similar to that shown in Fig. 2, with the flaps in position to be sealed: the gummed surfaces in this view being indicated

25 by small elevations.

The reference letter *a*, designates the body of the envelop blank, having the broad side flap *b*, and the narrow, gummed, opposite, side flap *c*, which are adapted to be folded over the body and sealed together, and also sealed to the body along the central adhesive surface *d*; thus forming two pockets joined at their inner ends.

30 The pockets are made separable by the central cross-perforations *e*. The increased thickness resulting from the overlapping of the flap *c* upon the broad flap *b*, is intentionally located near one side of the body *a*, in order to bring out distinctly the date and 35 number, when printed with other less important matter on the front of the envelop.

The sealing flaps *f* and *g*, are made with different outlines, to guide the contributor to the proper receptacle for each particular contribution, in accordance with instructions,

which may be printed on the front of the envelop, or announced orally, to the congregation. Thus flap *f* is shown to be pointed in Fig. 1, but it might as well be made crescent shaped or of any other outline, which would 50 be diverse from that of flap *g*.

In Fig. 1, flap *f* is shown to be gummed in the usual way for envelopes, but the modification *f'* seen in Fig. 2 is quite narrow and is not gummed, the part *j* of flap *g* sealing 55 down the flap *f'* upon its pocket. When the flap *f* shown in Fig. 1 is employed, it is folded down and sealed over its pocket, and the part *j* of flap *g*, is sealed upon it, so that whichever form of flap *f* or *f'*, is used, the 60 outer ends of the pockets are sealed together thus reducing the length of the device one half, and making it more convenient for handling or packing. In order to separate these sealing flaps, the flap *g* is torn along 65 its perforations *h*, and the pockets are entirely separated by tearing along the perforations *e*.

The flap *g* is dry-gummed, receives the perforations *h*, and is folded back upon itself, 70 during the process of manufacture; so that it needs only to be moistened to be ready for sealing its own pocket, or to be attached to the flap or body, or both flap and body, of the other pocket.

What I claim and desire to secure is,—

An envelop having two pockets joined at their bottoms and foldable together with 75 their sealing flaps facing each other, a flap on one of said pockets of any preferred construction and a cross perforated sealing flap on the other pocket adapted to seal both pockets and permit them to be separated.

In testimony whereof I affix my signature, in presence of two witnesses.

LYMAN R. SWETT.
